UNITED STATES PATENT OFFICE.

EDWARD H. BELDEN, OF TOLEDO, OHIO, ASSIGNEE, BY MESNE ASSIGNMENTS, TO THE WILLYS-OVERLAND COMPANY, OF TOLEDO, OHIO, A CORPORATION OF OHIO.

CONTROL MECHANISM.

Application filed October 13, 1917. Serial No. 196,520.

To all whom it may concern:

Be it known that I, EDWARD H. BELDEN, a citizen of the United States, residing at Toledo, in the county of Lucas and State of Ohio, have invented certain new and useful Improvements in Control Mechanism, of which I declare the following to be a full, clear, and exact description.

This invention relates to improvements in mechanism for controlling motor vehicles and the lighting circuit thereof.

The principal object of my invention is to provide an improved control board which is provided with a switch for controlling the ignition circuit and the headlight circuit, so as to dim the headlights, and with means for controlling the spark and throttle, and for choking the carburetor in starting. A further object of my invention is to provide a new and improved switch for dimming the headlights, combined with means for controlling the ignition circuit. A further object of my invention is to provide new and improved means for controlling the spark, throttle, and the carburetor choke valve.

Further objects, and objects relating to economies of manufacture and details of construction, will definitely appear from the detailed description to follow.

I accomplish the objects of my invention by the devices and means described in the following specifications. My invention is clearly defined and pointed out in the appended claims.

A structure constituting a preferred embodiment of my invention is illustrated in the accompanying drawing, forming a part of this specification, in which

Figure I is a front plan view of a switch board constructed in accordance with my invention.

Figure II is a view in rear elevation of the control switch shown in Fig. I, with the wiring of the ignition and lighting circuits represented diagrammatically.

Fig. III is an enlarged, detail, sectional view, taken substantially on the line III—III of Fig. I.

Fig. IV is a view, in front elevation, of the switch block with the face plate removed.

Fig. V is a detail, fragmentary, sectional view, taken substantially on the line V—V of Fig. III, and

Fig. VI is a perspective view of the switch plug.

In the drawings, similar reference numerals refer to similar parts throughout the several views, and the sectional views are taken looking in the direction of the little arrows at the ends of the section lines.

Considering the numbered parts of the drawings, I have shown a control board comprising the face plate 10, which is adapted to be secured to the instrument board 11, and which has secured thereto a switch block 12 made of any suitable insulating material and provided with the ears 13, through which the bolts 14 pass, securing the switch block to the face plate 10, and securing the whole in place on the instrument board 11. The nuts 15 are threaded on the rear ends of the bolts 14 and hold the switch block in place. The ears 13 are thicker than the body of the switch block 12, so that the chamber 16 is formed between the face plate 10 and the switch block 12, and a cylindrical recess or chamber 17 is formed in the central part of said switch block 12. A hub 18 of conducting material is journaled in an opening formed in said switch block 12, being disposed in the recess 17. A contact strip 19 is mounted on the front face of the switch block, and the upper end of said contact strip is electrically connected with a screw 21, passing therethrough and through the switch block 12, said screw having a terminal nut 22 threaded on the rear end thereof. The lower end of the strip 19 is bent rearwardly at 23 into the recess 17, and is electrically connected with the block 18, journaled in said switch block.

A screw 24 is mounted in the lower part of the switch block 12 and has the terminal nut 25 threaded on the rear end thereof. Said bolt 24 passes through the lower end of the contact strip 27 and the latter is held in place by the nut 26, threaded on the bolt 24. Said contact strip 27 extends upwardly from the lower part of the switch block, being spaced from the body thereof, and has its upper end curved rearwardly, as shown at 28. Said contact 27 is electrically connected with the terminal bolt 24. A switch plug is provided having a cylindrical shank 29, which is provided with an operating button 30, and journaled in a bushing 31 carried by the face plate 10. The shank

- 29 has a flattened portion 32, and a reduced rear end 33, which is adapted to engage the curved upper end 28 of the contact 27, when the switch plug is in place.
- 5 The shank 29 of the switch plug is provided with a groove 34, which is adapted to be engaged by the spring arms of the fork 35, secured to the switch block 12 by the screw 36, so that said spring fork serves as
- 10 a detent to hold the switch plug in its operative position when it has been inserted in the switch.

An arm 37 is mounted on the rear face of the hub 18 and is riveted or otherwise secured thereto, so as to rotate therewith. Said arm 37 is provided with an opening, having a flattened side, through which opening the switch plug 29 may be inserted with the flattened portion 32 engaging the 20 flattened side of the opening 38. The hub 18 and the arm 37 carried thereby may be rotated by turning the switch plug 29. A resistance coil 39 is mounted on the rear face of the switch block 12, around the 25 raised central hub 40 of the switch block. One end of said resistance coil passes through an opening 41 in the switch block 12 and is secured by and connected to a screw 42. The opposite end of said resistance coil passes through a similar opening 43, and is connected to a terminal 44. The lower end of the arm 37 is concave-convex in cross section, as clearly shown in Fig. V, and, when the switch plug is rotated in its 30 bearing 31, the convex face of said arm engages the surface of the resistance coil 39, so as to make electrical contact therewith. The switch block has a concave seat engaged by arm 37 when in normal position.

The lower part of the face plate 10 is provided with an upwardly and forwardly extending boss 45, having bearings for three 45 slidable plungers 46, each of which is provided with a head 47 by means of which it may be operated. Each plunger 46 is provided with a plurality of annular grooves 48 therein. A flange 49 extends downwardly and rearwardly from the boss 45, lying above the plungers 46, and three leaf springs 50 are secured to the flange 49 by the rivets 52 and have curved forward ends 51, which are adapted to engage and seat in any one of the grooves 48, as clearly 55 shown in Fig. III. The rear end of the flange 49 is bent over at 53, embracing the forward ends of the tubes 54, in which the control wires 55 move. The forward end of each of said wires is bent to form a hook 60 56, which is connected with the lower end of the corresponding plunger 46.

In the diagrammatic illustration of the wiring, shown in Fig. II, the storage battery or other source of current is represented at 57, the circuit breaker at 59, and the

primary winding of the ignition circuit at 60. The battery 57 is connected by wire 61 with the terminal 21 of the switch. The opposite side of the battery 57 is connected by wire 62 with the circuit breaker 59. Said wire 62 is connected by the wire 63 with the lamps 58, the other side of said lamps being connected by the wire 64 with the terminal 42, connected to one end of the resistance coil, as I have heretofore described. Terminal 24 is connected by the wire 65 with one end of the primary winding 60 of the ignition circuit, the other end of said winding being connected with circuit breaker 59.

From the description of the parts given above, the operation of this device should be very readily understood. The parts of the switch are shown in the position, in which the ignition circuit is closed and the headlight circuit is broken. The removal of the plug 29 breaks the ignition circuit, because this circuit is closed by the contacting of the reduced end 33 of the plug with the contact arm 27, said contact arm 27 being connected through the terminal 24 with one branch of the ignition circuit, while the plug 29 is connected through the hub 18, strip 19 and terminal 21 with the other branch of the ignition circuit. The unintentional removal of the plug is prevented by the detent comprised by the spring fork 35, the spring arms of which engage in opposite sides of the groove 34, formed in the shank 29 of the switch plug.

As I have already stated, the parts are shown in the position in which the headlight circuit is broken. When the switch plug is rotated to the left, in Fig. I, the arm 37 will be moved to the right, in Fig. II, and the headlight circuit will be closed from the wire 64, through the terminal 42, the resistance coil, and from the resistance coil through the arm 37, hub 18, strip 19, terminal 21, wire 61, battery 57, wire 62 and wire 63 to the other side of the headlights. Since the arm 37 is so disposed with reference to the resistance coil that it engages said coil very close to the end thereof, a very small amount of said resistance coil will be included in the circuit, and therefore the lights will be bright. If the operator desires to dim the lights, this can be done by rotating the switch plug to the left, in Fig. I, so as to move the arm 37 to the right, in Fig. II, including a greater portion of the resistance coil in the circuit. The same results can be accomplished more quickly by turning the switch plug to the right, in Fig. I, which will move the arm 37 to the left, in Fig. II, engaging the opposite end of the resistance coil 39 from that to which the circuit 64 is connected, so that practically the entire resistance is included in the headlight circuit and the headlights will be dimmed at once. The

amount of light given by the headlight can be varied by moving the switch plug so as to position the arm 37 to include a greater or lesser amount of resistance in the headlight 5 circuit and this feature of operation will be apparent from the drawing. The lower end of the arm 37 is slightly concave-convex in cross section, as illustrated in Fig. V, and the switch block 12 is provided with 10 a concave seat so as to hold the arm in neutral position and prevents its moving out of that position except when operated.

I have combined with this headlight dimming switch an engine control board, 15 so that both the ignition and lighting circuits and the spark, throttle and choke valve are controlled from the same board. The mechanism by which the spark, throttle and choke are operated is the same in each case, 20 and a description of one of these will suffice. I provide plungers 46 slidably mounted in the boss 45 on the lower part of this control board, each of said plungers being adapted to be held in any one of a plurality of positions as defined by the grooves 48. The 25 spring 50 serves as a detent to retain the plunger 46 in the position to which it has been adjusted. The lower end of the plunger 46 is connected with the wire 55, 30 the movement of the plunger being transmitted through the wire 55, to the proper levers for controlling the spark, throttle or choke as the case may be.

I am aware that the particular embodiment of my invention, which I have here shown and described, is susceptible of considerable variation without departing from the spirit thereof, and, therefore, I desire to claim my invention broadly, as well as 35 specifically, as indicated by the appended claims.

Having thus described my invention, what I claim as new and desire to secure by Letters Patent, is:—

1. A device of the class described comprising the combination of a face plate; a switch block secured thereto; a resistance coil carried by said switch block, one end of said coil being connected with a terminal; a metallic hub journaled in said switch block and electrically connected with a second terminal; a contact arm carried by said hub and adapted to engage said resistance coil; a second contact arm carried by said switch block and electrically connected with a third terminal; and a switch plug insertable through said face plate, journaled therein, and having a non-rotatable connection with said hub, said switch plug 50 being adapted to contact with said second contact arm, when inserted in position, and being rotatable to rotate said first-named contact arm and move the same in contact with said resistance coil.

2. A device of the class described com-

prising the combination of a face plate; a switch block secured thereto; a resistance coil carried by said switch block, one end of said coil being connected with a terminal; a metallic hub journaled in said switch block and electrically connected with a second terminal; a contact arm carried by said hub; a second contact arm carried by said switch block and electrically connected with a third terminal; a switch plug 70 insertable through said face plate and journaled therein, having a non-rotatable connection with said hub, said switch plug contacting with said second contact arm, and being rotatable to move said first-named contact arm in engagement with said resistance coil; and a detent for holding said switch plug in inserted position.

3. A device of the class described comprising the combination of a face plate; a switch block secured thereto; a resistance coil carried by said switch block; a metallic hub journaled in said switch block, ignition and headlight circuits including said hub; a contact arm carried by said hub and 80 adapted to engage said resistance coil, one end of said resistance coil being connected in said headlight circuit; a second contact arm carried by said switch block and electrically connected in said ignition circuit; and a switch plug insertable through said face plate and engaging said second contact arm to close the ignition circuit, and having a driving connection with said hub, whereby the rotation of said switch plug moves 90 said first-named contact arm in contact with said resistance coil to vary the amount of resistance in said headlight circuit.

4. A device of the class described, comprising the combination of a switch block; a resistance coil carried thereby; a hub journaled in said switch block, ignition and headlight circuits including said hub; a contact arm carried by said hub and adapted to engage said resistance coil; a second contact arm carried by said switch block and connected in the ignition circuit; and a switch plug insertable in said switch block to close the ignition circuit and rotatable to vary the amount of resistance in said headlight circuit.

5. A device of the class described comprising the combination of a switch block; a resistance coil mounted thereon; a lighting circuit including said resistance coil; a contact arm rotatably mounted on said switch block and connected in said lighting circuit; a switch plug insertable in said block and adapted to close the ignition circuit on its insertion and rotatable to move said contact arm in engagement with said coil.

6. A device of the class described comprising the combination of a switch block headlight and ignition circuits; a resistance coil carried by said block and having one 120

- terminal connected in said headlight circuit; a contact arm rotatably mounted on said switch block and electrically connected with the headlight and ignition circuits; and a 5 plug inserted to make an electrical connection between said arm and a contact to close the ignition circuit, and rotatable to carry said arm in engagement with said resistance coil to vary the amount of resistance in said 10 circuit.
7. A device of the class described comprising the combination of an ignition circuit and a lighting circuit, a resistance coil connected in said lighting circuit, a contact 15 arm adapted to engage said resistance coil and vary the amount of resistance in said lighting circuit, and a removable plug adapted to close the ignition circuit and at the same time operate the contact arm to 20 vary the resistance in the lighting circuit.
8. In a device of the class described comprising the combination of an ignition circuit and a lighting circuit, a switch block through which the said circuits are completed, a resistance coil carried by said 25 block and connected with said lighting cir-
- cuit, a contact arm adapted to engage said resistance coil and vary the amount of resistance in said lighting circuit, a plug insertable in said block to close the ignition 30 circuit and at the same time operate the contact arm to vary the resistance in the lighting circuit, and means for releasably holding the plug in the switch block.
9. A device of the class described, comprising the combination of a multiple circuit including an ignition and a lighting circuit, a rheostat connected in said lighting circuit, and a plug detachable to open 35 said ignition circuit and rotatable to operate said rheostat.
10. A device of the class described, comprising the combination of an ignition circuit and a lighting circuit in multiple, and means operable to vary the intensity of the 40 lighting circuit, a portion of said means being detachable and forming a part of said ignition circuit.

In testimony whereof I affix my signature.

EDWARD H. BELDEN.
